Primary Examiner — Sandra L Morris(74) *Attorney, Agent, or Firm* — Jeffer Mangels Butler & Mitchell LLP; Brennan C. Swain, Esq.**CLAIM**

The ornamental design for a bottle, as shown and described.

DESCRIPTIONFIG. 1 is a perspective view of the present invention;
FIG. 2 is a front elevational view of the present invention,
the right side elevational, left side elevational and rear
elevational each being a mirror image thereof;

FIG. 3 is a top plan view of the present invention; and,

FIG. 4 is a bottom plan view of the present invention.

The shading shown in the drawings is for illustrative purposes only and forms no part of the claimed design.

1 Claim, 4 Drawing Sheets(56)
